BANK SERVICE MECHANISM FOR
AUTOMOBILES

Melvin S. Buros, Phoenix, Ariz., assignor to Diebold,
Incorporated, Canton, Ohio, a corporation of Ohio
Filed Mar. 17, 1961, Ser. No. 96,434
1 Claim. (Cl. 186—1)

This invention concerns bank service mechanism for automobiles.

One of the objects of the invention is to provide a teller's service drawer which operates in structure made a part of a bank teller's cage included in an outer wall of a building and disposed adjacent to a driveway so that automobiles positioned in the driveway can have ready access to the teller's drawer with a minimum of movement on the part of the automobile and so that the teller on the inside of the wall has ready access to the drawer when it is withdrawn into the wall.

Another object is to provide a bank teller's outside service drawer combined with wall structure which will be readily adjustable vertically and will move in and out of the wall structure at any vertical position desired.

Still another object is to provide a structure and mechanism which will support and operate a bank teller's drawer so that it can be raised or lowered to any desired level and then operated outward to a position adjacent the body of a parked automobile and may then be withdrawn into the wall so that a teller in a cage on the inside of the wall may have ready access to the contents of the drawer.

Still another object is to provide a unit structure for holding and operating a bank teller's outside service drawer that can be readily installed in the wall of a building or a service bay that will provide a theft proof service structure that contains all the necessary working parts to operate the service drawer up and down and in and out with reference to the point of service outside the wall and which unit may be readily installed in an opening in a wall of a bank or service bay therein.

only one levelling and truing operation.

Still another object is to provide a service drawer operating mechanism wherein all critical parts are protected from the fire of hold-up weapons and wherein the operating parts are securely protected behind or in the outside wall of a bank or service bay therein.

Still another object is to provide the means for rendering the moving parts of the service drawer weather proof and proof against the loss of coins or the like within the teller's cage.

Still another object is to provide the service drawer operating unit with means of easy access and means for support to obtain vertical adjustment of the service drawer's structure using a minimum number of supporting parts.

I attain the foregoing objects by means of the structure, parts and combinations of parts shown in the accompanying drawings, in which—

FIGURE 1 is a plan view of a service unit installed in the wall of a bank building and exposed on the outer wall and opening into a teller's cage on the inside of the wall;

FIGURE 2 is a front elevational view of the installation referred to in FIGURE 1;

FIGURE 3 is a side elevational view, partially in section of the installation shown in FIGURE 2;

FIGURE 4 is an elevational view of the service drawer installation as viewed from the inside of the building adjacent the wall;

FIGURE 5 is a fragment of the moving service unit and the adjacent confining structure showing a means and rendering the sliding joint between the moving and the stationary elements tight and proof against the loss of

2

coins or small objects in portions of the opening occupied by the service unit;

FIGURE 6 is a plan view of the unit drawn on a somewhat larger scale and sectioned off in part to show the supporting mechanism for the service drawer;

FIGURE 7 is a side elevational view of the structure shown in FIGURE 6;

FIGURE 8 is a section taken substantially on line 8—8 of FIGURE 2 and drawn on a greatly enlarged scale showing means of slidably supporting the movable drawer of the service unit in the supporting frame of the entire device;

FIGURE 9 is a isometric view of the service unit and connecting parts all drawn on a somewhat enlarged scale;

FIGURE 10 is a plan view of the lower part of the case containing hydraulic operating units;

FIGURE 11 is a plan view of the lower part of the operating mechanism;

FIGURE 12 is an end view of the operating mechanism; and

FIGURE 13 is a side view thereof.

Similar numerals refer to similar parts in the several views.

In the first four views 2 indicates the wall in which the service unit is to be installed. 3 indicates the service unit in general. 4 indicates the glass portion of the wall above the level of the counter 5. Numeral 6 designates the unit which is installed in wall 2 and which contains the operational parts necessary to make the drawer 10 function as desired. That is, to cause the drawer to move to various horizontal levels as indicated by arrow 11, in FIGURE 3, and to move in and out away from and toward the outer face 12 of wall 2, as indicated by arrow 14, FIGURE 3.

As shown in FIGURE 1 the unit 3 is installed within wall 2 at the front and with its top within and level with the counter 5. As viewed in FIGURE 2, only the outside of the unit 3 is shown and the inner operative parts are not visible. As shown in FIGURE 4 the unit 3 has been installed in the front wall 2 of the building and its upper part extends into the glass window 4. The body of the unit 6, which contains the working parts of the unit includes a movable part 25 which has a flat top with an opening so that the teller will have access to the drawer 10, as shown at 15, FIGURE 6. When the drawer 10 is extended, as partially indicated in FIGURE 7, it protrudes outward from the upper part of the case portion of the unit 3. A rectangular frame 16 is attached to the body 6 at its forward end and is used as a base in which to fit the forward or outer portion of the unit

3 into the wall and particularly into the glass portion of the window 4. This frame acts as a guide for a sliding protective shield plate 17, made of transparent material such as heavy plastic, or the like. This plate slides upward through a slot in the top member of frame 16 and is disposed upward just in back of and parallel to the window glass 4. This shield plate 17 forms a covering for the opening in the wall and the glass that is necessary to permit movement of the drawer 10, as hereinafter explained. The upper movable part 25 telescopes over the lower body part 6, slides in vertical frame 16, and carries drawer 10.

Apparatus, auxiliary to the operation of apparatus, such as the speakers 18 and 18a, is included in the unit 6 as is the apparatus for operating the microphone 19 and other auxiliary apparatus. These items are not a part of the invention.

The body of the unit 3 rests on a base or foundation pan 23 which is set into the cement 24 of the floor and foundation at the time these items are poured. This foundation pan has a rectangular open interior 26 extending from its bottom 27 to the top rim 28. This rim is made of angle iron or its equivalent and provides a

flat flange 28a around the entire top edge of the rectangular box body of the pan. This flange is provided with holes to receive bolts which secure mating holes in the flanges 30 on the body of unit 3. The service drawer 10 is, in the form shown, a rectangular drawer with the front closed by plate 31 and the back closed by a similar plate. There is room on the inside of the drawer to receive money, papers, books or the like used in the bank service operations. The drawer slides in and out of a movable upper part or frame structure 25 and this structure is movable in the outer stationary frame 16. The drawer is operated by hydraulic means including a piston operating in a cylinder 65 when oil under pressure is introduced into the cylinder in a conventional manner. The inner movable frame 25 is raised and lowered by a supporting piston rod or ram 33 which is also operated by oil under pressure introduced into a cylinder in which the ram 33 operates. The controls for this mechanism are contained in a box 35 and operate through electrical wiring 36 to control valves and motor driven pumps within the area 37 of unit 3.

In order to slidably support the frame 25 which holds the sliding drawer 10, I provide the two rollers 40 and 41 which run in vertical channels 45 in inner face of the rear portion of the slide members 46 of frame 16. These rollers guide the motion of the drawer frame 25 and support the rearwardly extending portion of the drawer in addition to the support afforded by piston rod 33. With this guiding means of support and the ram piston 33 no other guides or supports are necessary to maintain the vertically moving frame 25. The guides and supports for the horizontally moving portion of the drawer proper are conventional and there is a horizontally extending cylinder 65 on the bottom of drawer 10 which has a piston attached to a stationary portion of the drawer frame 25 so that introduction or removal of hydraulic fluid into or from the cylinder will operate the drawer in and out as desired. This motion is also controlled by mechanism within space 37 of the unit 3 and controlled by conventional device in the box 35. This box may be set on or below the counter 5, as shown in FIGURE 4.

In the installation of this type of mechanism difficulty has heretofore been experienced in getting the moving parts coordinated with the wall structure so that they do not cramp or bind. With this mechanism it will be noticed that the frame 16 is disposed at the front of unit 3 and made a part of it and that the guide channels for the plate 17 are on the inner faces of this frame and are mated with the slot 49 through which the movable glass 17 extends. The movable part of the drawer 10, supported by rollers 45 in grooves 50 are also a part of the frame. Unit 3 is self-contained and can be prepared and assembled at the factory. After the base pan 23 is installed and set in the cement foundation it is only necessary to set the unit in place on it and then add the adjoining parts of the wall 2 so that they abut the sides of the frame 16. The glass 5 is cut with a notch to fit around the frame and then set in place with the edges of the notch bearing on the sides and top of the frame 16. This substantially completes the installation and no truing up of the guide slots is necessary.

Within the cabinet 3 there is operating mechanism consisting chiefly of a motor 60 which operates a fluid pump 61 and delivers fluid, such as oil or the like to each of two hydraulic rams 33, which is used to raise and lower the upper frame part 25 of the drawer mechanism and to cylinder 65 which controls the in and out movement of the drawer 10.

The oil pressure is controlled by a regulator 66 in any well known and conventional manner so that both cylinders will have limited force but will operate smoothly throughout the range desired. The controls for the valves that operate both 33 and 65 are contained in box 35, as above mentioned, and operate the valves by elec-

trical means through cables as above mentioned. The drawer 10 is operated by the cylinder and piston 65 so that it has sufficient outward thrust for all practical ordinary purposes but at the same time if it encounters an immovable objects the oil pressure will be shunted through a limit valve 67 and the drawer will not advance against the positive resistance so as to cause damage.

It is to be noted that, as shown in FIGURE 10, the horizontal drawer operating mechanism is beneath the drawer and on top of the mechanism in the cabinet. Since the drawer moves relative to the mechanism in cabinet unit 3, connection is made through flexible tubing 69 and 70.

From the foregoing it will be noted that the drawer supporting frame portion 25, which includes the guide on which the drawer operates horizontally, is supported in the vertical frame 16 by the two rollers 40 and 41.

This structure permits the drawer carrying frame 25 to move up and down within the stationary frame 16 and, within the limits of this travel, the drawer may be independently moved to or from its serving position as indicated in dotted lines in FIGURE 3. The drawer may thus serve automobiles with high windows such as trucks or the lower windows such as are found in compact cars, all with equal efficiency.

Since the upper outer part 6 of unit 3 moves up and down with reference to counter 5 and the fittings and furniture within which the device is installed, I provide the mechanism shown in FIGURE 5 to form a seal between the moving and the stationary parts. In this figure the sides of the opening in the counter in which the device is installed are indicated by numeral 90. Over this side member an angle iron strip 71 is attached. This strip has its flat vertical face 72 closely adjacent to the vertical face 73 of the moving part of the cabinet. A brush like closure element 74 is attached to the top of the vertical face 72 of strip 71. The bristles of this brush are sufficiently stiff to deter the entrance of any small objects into the space 75 between the faces 72 and 73. Thus, coins, pencils or the like will not drop down from the top area 76 to the space 77 along the side of the cabinet, but the part 6 is free to move within counter 5.

Having now described my invention and explained its use I wish to be limited only by the following claim.

I claim:

Bank service mechanism for automobiles consisting of a unit to be installed in the outer wall of a bank teller's compartment, including a base pan set into the floor of said compartment having a flanged upper edge, a stationary case unit containing the working parts of the device having bottom flanges resting on the flange on said base pan, a rectangular vertical frame having vertical side members and horizontal top and bottom members attached to said stationary unit and adapted to be set into said walls, said vertical frame members having slots in the forward portion thereof to receive the edges of a sliding transparent panel, and having slots in the rear portion thereof to receive rollers on a movable frame structure, a movable frame structure having rollers engaging in the rear slots in said vertical frame members to slidably support said movable frame so that it will slide within said vertical frame and telescope over said stationary case unit; said movable frame structure having a top with an access opening to expose the sliding door on the interior of said frame; said top vertical frame member having a slot to slidably receive a vertical transparent panel; a vertical transparent panel attached to the top of said movable frame structure and disposed to slide through said slot; a hydraulic ram piston on the bottom of said movable frame structure operating in a cylinder in said stationary case unit to support said movable frame structure and afford means for vertical movement of said frame structure, a teller's drawer slidably mounted in said movable frame structure to slide in and out of said structure horizontally with reference to said vertical

frame; a hydraulic piston and cylinder on said frame to provide support and sliding motion for said movable frame; hydraulic mechanism for independently operating said ram piston and said piston and cylinder on said drawer; a counter on the frame structure above the drawer and having a drawer access opening to receive the lower stationary body part of said bank service apparatus and a strip of metal material having a brush attached on one side and directed toward the adjacent side of said body; and said brush being in movable contact with said movable frame on said stationary body part, to prevent

small articles from falling from said counter into space between said body part and said counter.
